UNITED STATES PATENT OFFICE.

JULIUS WODISKA, OF NEW YORK, N. Y.

DESIGN FOR A FINGER RING, PIN, BROOCH, OR SIMILAR ARTICLE.

Application filed January 22, 1921. Serial No. 439,305. Term of patent 3½ years.

To all whom it may concern:

Be it known that I, JULIUS WODISKA, a citizen of the United States, and resident of the borough of Manhattan, city, county, and State of New York, have invented a new, original, and ornamental Design for a Finger Ring, Pin, Brooch, or Similar Article, of which the following is a specification.

Reference is to be had to the accompanying drawings in which, for convenience of

illustration, the invention is shown as incorporated in a finger ring and in which Fig. 1 is a side view of such a ring showing the design and Fig. 2 is a plan view thereof.

I claim:

The ornamental design for a finger ring, pin, brooch or similar article substantially as herein shown.

JULIUS WODISKA.
